UNITED STATES PATENT OFFICE.

FRANK A. REILLEY, OF PORT CHESTER, NEW YORK.

HEATER FOR APPLYING AND MELTING WAXES, PARAFFINS, SOLDERS, AND SIMILAR SUBSTANCES.

No. 897,782.

Specification of Letters Patent.

Patented Sept. 1, 1908.

Application filed July 17, 1907. Serial No. 384,263.

To all whom it may concern:

Be it known that I, FRANK A. REILLEY, a citizen of the United States, residing in the village of Port Chester, in the county of 5 Westchester, State of New York, have invented a new and useful heater for melting and applying waxes, paraffins, solders, and similar substances, which heater will herein-after be designated as a "wax melting and 10 applying machine," of which the following is a specification.

This invention relates to a device for melting and applying wax, paraffin and the like, and relates more particularly to a device of 15 that type in which the heat is furnished by a current of electricity traversing coils or heating units suitably arranged on the vessel or crucible that holds the wax, paraffin or the like.

20 The invention has for one of its objects to improve and simplify the construction and operation of devices of this character so as to be comparatively easy and inexpensive to manufacture, thoroughly reliable and efficient in use, and readily manipulated.

25 A further object of the invention is the provision of a vessel of suitable design on which are permanently arranged heating units or coils for melting the wax or paraffin 30 by heat transmitted through the walls of the vessel, the flow of current through the coils being controlled by a switch arranged on the handle of the vessel so that different degrees of heat can be obtained, if desired.

35 Another object of the invention is the employment, in connection with a device of this character, of a valve for controlling the discharge of melted wax or paraffin, the valve being operated by a lever mounted in such a 40 position that it can be conveniently actuated by the same hand which holds the handle of the device.

With these object in view and others, as will appear as the description proceeds, the 45 invention comprises the various novel features of construction and arrangement of parts which will be more fully described hereinafter and set forth with particularity in the claims appended hereto.

50 In the accompanying drawing, which illustrates one of the embodiments of the invention, Figure 1 is a central vertical section taken through the vessel or crucible with parts of the device in elevation. Fig. 2 is a

side view of the device with a portion of the 55 handle broken away.

Similar reference characters are employed to designate corresponding parts throughout the several views.

Referring to the drawings, A designates a 60 stand for holding the device during the mounting operation or when the device is not in use, the stand consisting of a ring 1 and legs 2 rigidly secured to the ring.

The device consists of a vessel or crucible B 65 which is open at its top and of cylindrical form at its upper portion 3 and tapers downwardly into a funnel portion 4. The funnel is contracted at 5 to form a seat 6 and below the seat is a discharge mouth 7 through which 70 the melted wax, paraffin or the like is delivered. Disposed around the tapering or conical portion of the crucible or vessel B are heating units 8 and 9 constructed of coils 75 of suitable wire and fixedly secured in position by a suitable insulating binding. These windings are suitably connected in series so that current can be passed through both of them when it is desired to obtain the lower degree of heat and one of the windings can 80 be cut out when it is desired to obtain a higher degree of heat.

Attached to the crucible B is a handle C which carries at its inner end a switch device 85 designated generally by D. This device 15 comprises contacts 10 and 11 with which operates a contact lever 12 pivoted at 13 on the plate 14, the lever and contacts being suitably insulated from the said plate. The plate, which may be of insulation, is secured 90 to the handle C by screws or other fastenings 15. The handle C is preferably hollow for receiving the lead-in wires 16 and 17 which are intended to be connected with a suitable supply circuit by a socket plug (not shown), 95 and the inner ends of the wires are connected respectively, with the screw or pivot 13 of the lever 12 and the binding post 18 on the plate 14. The switch device is connected with the heat coils by the wires 19, 20 and 21. The 100 wire 19 connects the inner coil 9 with the binding post 18 and the wire 21 connects the outer coil 8 with the contact point 11, while the wire 20 connects the contact point 10 with an intermediate point of the wire of 105 which the two coils 8 and 9 are composed. It will be noted that the lever 12, which has a knob 22, is located in such a position that

it can be moved back and forth by means of the thumb of the hand grasping the handle C of the device. When the lever is in engagement with the contact 11, the current will 5 pass through the wire 16, lever 12, contact 11, wire 21, both coils 8 and 9, wire 19, binding post 18, and wire 17. Since both resistance or heating coils are in circuit, less current will pass and consequently the lower 10 heat will be obtained. When it is desired to obtain a higher heat, the lever 12 is moved into engagement with the contact 10 so that the current will traverse only the inner coil or heating unit 9. Arranged within the 15 crucible is a valve 23 of suitable form that is carried on the lower end of a stem 24 which projects out of the crucible at the top, where the stem is hingedly connected at 25 with the front end of an actuating lever 26. This 20 lever is fulcrumed at 27 on the inner end of the handle and the rear end is formed into a thumb piece 28, whereby the operator can depress the lever to unseat the valve when it is desired to permit some of the melted par- 25 affin or wax to discharge from the mouth 7. The parts are so arranged that the valve will tend to gravitate to its seat but it may be desirable to provide positive means for seating the valve, such as a spring 29 secured to 30 the handle 30 with one end pressing on the thumb piece 28 so as to operate through the lever and valve stem to hold the valve against its seat.

From the foregoing description, taken in 35 connection with the accompanying drawing, the advantages of the construction and of the method of operation will be readily apparent to those skilled in the art to which the invention appertains, and while I have de- 40 scribed the principle of operation of the invention, together with the apparatus which I now consider to be the best embodiment thereof, I desire to have it understood that the apparatus shown is merely illustrative,

and that such changes may be made when 45 desired as are within the scope of the claims.

Having thus described the invention, what I claim is:

1. In a device of the class described, the combination of a crucible open at its top and 50 provided with a discharge mouth at its bottom, a seat at the mouth, a valve arranged to engage the seat, a stem rigidly connected with the valve and supporting the same, a handle connected with the crucible adjacent 55 the top thereof, a lever connected with the upper end of the valve stem, means for fulcruming the lever on the inner end of the handle and above the latter, a finger piece on the outer end of the lever and projecting 60 over the handle, and a spring secured to the handle and bearing on the lever to hold the valve seated, with a switch mounted on the handle at the side thereof, and a heating coil on the crucible and controlled by the switch. 65

2. In a device of the class described, the combination of a crucible tapering downwardly to form a contracted mouth, a valve seat at the mouth, a valve arranged to engage the seat, a stem connected with the 70 valve, a hollow handle attached to the crucible, a bracket on the inner end of the handle, a lever pivoted intermediate its ends on the bracket, a hinge connection between one end of the lever and the upper end of the stem, 75 the opposite end of the lever projecting over the handle, a sectionalized heating coil secured around the outside of the crucible, and a switch device mounted on the handle and comprising contact points connected to different parts of the heating coil, a lever movable into and out of contact with the points, a lead wire connected with the switch lever, and a wire connected with one end of the coil. 80
